UNITED STATES PATENT OFFICE.

NELSON CROSS, OF NEW YORK, N. Y.

IMPROVED FOLDING CHAIR.

Specification forming part of Letters Patent No. 35,993, dated July 29, 1862.

To all whom it may concern:

Be it known that I, NELSON CROSS, of the city, county, and State of New York, have invented a new and Improved Folding Chair Suitable for Tourists, Excursionists, &c.; and I do hereby declare the following to be a full and exact description thereof, reference being had to the accompanying drawing, as subdivided and explained.

The nature of my invention consists of the construction of a strong, light, and comfortable chair, capable of sustaining a heavy weight and susceptible of being easily folded into a narrow and compact space. The material used in its construction is, with the exception of the metallic fastenings, wood. Hickory, oak, and ash will be found preferable to most other woods found in this country. A single isometric representation of the chair is shown, as it is believed this will subserve every required purpose. In order to a clear understanding of this, I have thought fit to subdivide the parts as follows, to wit:

Subdivision 1, consisting of the cross standards or supports; subdivision 2, consisting of the seat; subdivision 3, consisting of the back; subdivision 4, consisting of the arms and armfastenings.

First subdivision—The lower part or base of the chair is composed of four slats or bars of wood of equal proportions, the inner two being framed parallel to each other and firmly held in place at a distance, measuring from their interior surfaces, equal to the width of the seat, by means of a cross tie or brace attached at the extremes of its four arms to the two bars midway between the upper and lower half of each, measuring from the center to the ends, by side mortises and tenons so framed as to detract as little as may be from the natural strength of the wood, thus uniting great strength and durability when the strain is severest by an economical expenditure of material. The two outer bars or slats are also united parallel to each other, at a distance sufficiently enlarged to admit of their working upon the outside of the two inner bars, by means of a straight tie or brace running at right angles, and attached in like manner to the under side of the lower half of the two outer bars, in such manner as to present no obstacle to the close folding of the various parts. The base-sections thus framed are

united midway between their extremes by a slim axle-bolt, thus forming a substantial base for the additional parts of the chair.

Second subdivision.—The seat is constructed of a number of thin slats extending from front to rear at right angles with the front outer bar, and passing between and immediately behind the interior back slats. They are securely attached at the ends to a front and rear cross-bar by means of dovetail joints or their mechanical equivalent. The front cross-bar forms the front or outer face of the seat, being the larger and stronger of the two. It is bored at the axis of the two ends to receive the axle-bolt, screw, or other fastening, and the two ends are bound with metallic rings to give it additional strength.

Third subdivision.—The back consists of two side slats or bars, a bottom rail or bar joined by a mortise and tenon within the same, a top rail or cap-piece joined in like manner, but projecting at the ends sufficiently to prevent the sliding arms from slipping over the top. Within this frame there are a number of thinner slats running parallel to the sides equidistant from each other, and arranged in juxtaposition to the horizontal slats of the seat. These at the bottom are let into the rear or back edge of the bottom rail, thus effectually resisting the strain upon the rear attachment of the seat, but at the top they are let into the front or inner edge of the cap-rail, the center one being dovetailed at the two ends, thus uniting the strength of the two end rails in sustaining the seat, and not only forming a smooth inner surface to the back, but also making room for the passage of the arms-bar into the slots or mortises of the side rails and immediately behind the thin slats of the back, against which it rests and serves to support, as hereinafter described.

Fourth subdivision.—The arms are formed of two parallel bars or slats of equal length and proportions, united at the upper or sliding end by a metallic rod or bar of sufficient length to pass at right angles to the arm-pieces behind and across the back and below and parallel with the top rail. The arms are fixed and held in position by means of an angular mortise or slot let into the sides of the back frame at the rear edge, thence passing downward through the same the distance of half an inch, (more or less,) and the arms-

bar is firmly locked in position by means of a metallic button, slide, or key, so adapted and attached as to fall or slide into place by its own gravity directly over the lower angle of the said mortise or slot and upon the arms-bar, thus preventing its escape. This fastening may be effected by other well-known mechanical contrivances.

The several parts or subdivisions above described are set up and put together in the following manner: The two outer standards or supports are carried back at the upper ends, the lower end of the back is passed between them, and a bolt, screw, or other fastening is then passed through the ends of these upright cross-supports into the outer frame of the back at a point immediately above the bottom slat or rail. Through the interstices of the back interior slats the horizontal slats of the seat are passed and permanently fastened to the rear bar of the seat immediately behind the said back slats, thus intersecting and fastening together the seat and back at the points stated. The forward or front bar of the seat is then passed longitudinally between the upper ends of the inner standards or cross-supports of the base. The upper or sliding part of the arms is passed over and behind the back. The lower ends are drawn down, so as to cover the upper ends of the two inner supports or cross-standards. A bolt, rod, or screw is then passed through the arms at the lower ends into and through the said inner supports at the point designated, and thence securely

into the axis of the forward bar of the seat, thus binding and holding the three firmly in place in such manner as to allow the arm-pieces and supports to turn upon the bolt-fastenings as upon an axle.

The chair is sustained in an upright position by raising the arms-rod and sliding it into the side mortises prepared for its reception, as above described. The back may thus be set to any required inclination, or different degrees of an angle may be attained for the back by a series of straight or angular cuts and fastenings, accordingly as may be desired.

The advantages which this chair possesses over all other folding chairs now in use are, first, great strength and durability, combined with lightness and portability, theseveral parts being so related to each other as to afford a mutual support, thus permitting the use of slender and delicately-fashioned bars in its construction; second, a simple and easy mode of adjustment for use, or of folding compactly together for transportation; third, facility of construction, the materials and workmanship being simple and easily procured.

That which I claim as my invention is—

The combination and arrangement of the seat and back with the movable or sliding arms and the arms-rod, substantially as and for the purpose specified.

NELSON CROSS.

In presence of—

EDWIN B. FORD,
EDWARD SHERER.
